CEMENTING

Arthur W. Smith and Ray A. Plummer, Houston, Tex., assignors, by mesne assignments, to Big Three Welding Equipment Company, Houston, Tex., a corporation of Texas

Filed Feb. 6, 1961, Ser. No. 37,208
7 Claims. (Cl. 166—21)

This invention pertains to the cementing of oil and gas wells, and in particular to the cementing of pipes disposed in such wells. It is customary in oil and gas petroleum wells that at least some of the pipes in the well be cemented over at least a part of their length in order that they will be held firmly in place in the well. The cement also serves the purpose of sealing off the well at the position of the cement so that egress or ingress of fluids between the well and the earth structure surrounding the well be reduced or eliminated.

A principal object of the invention is to provide methods for cementing oil or gas wells.

Another object of the invention is to provide such methods which are safe, economical, simple to perform, and yet are dependable.

A further principal object of the invention is to provide cementing methods for oil or gas wells which provide superior cementing thereof.

Briefly, the invention contemplates gasifying or aerating drilling fluid mud in a well with an inert gas such as nitrogen or carbon dioxide so that the weight of the mud is reduced. The mud may be any type of drilling fluid known in the art. With the mud weight decreased, cement may be run into the well behind the mud more efficiently and with less chance of breaking down of the formation around the well due to a high weight or pressure of mud or cement thereon. Less pressure must be imposed on the cement slurry while it is being pumped into the well in order to displace the mud and move the cement slurry to the proper position in the well, usually around the exterior of the lower end of a casing or tubing. The mud of lighter weight than normal is displaced by the cement slurry more readily so that excessive pressure does not act on the formation surrounding the zone to be cemented.

Other objects and advantages of the invention will appear from the following detailed description of preferred embodiments thereof, reference being made to the accompanying drawings, of which:

FIGURE 1 is a vertical cross-sectional view in schematic representation showing a well adapted for employment of the invention, with the apparatus shown in use during one stage of performance of the method; and

FIGURES 2-6 are each similar to FIGURE 1 showing different stages during performance of the method.

Referring now to the drawings in detail, and first to FIGURE 1, there is shown a well 10 having therein an upper casing 11, usually called the surface or conductor casing. As is customary, the casing 11 may be replaced by a plurality of outer casings of different lengths extending down into the well to different depths. Each of these casings may be treated for cementing purposes in accordance with the description herewith presented for the inner casing 12. Casing 12 is received through any suitable surface apparatus which may be provided to perform the described functions of the well head members hereinafter mentioned. The well head members shown in FIGURE 1 of the drawings are casing head 13 supported at threaded connection 14 at the upper end of casing 11 above the earth's surface 15, tandem blowout preventer devices 16, 17, and adapter body 18 connected to the upper end of inner casing 12, for example at a

2

threaded socket formation (not shown) within enlarged lower portion 18a of body 18, or in other suitable manner. A lubricator device 18b seals the upper end of body 18, or other seal means may be employed.

Body 18 has side outlet 19 to which is connected a pipe 20 or other conduit means including a valve 21 and a gas jet or nozzle 22. A branch line 23, including valve 24, leads from a cement supply source 25 into line 20 between body 18 and valve 21 at T connection 26. Nozzle 22 has side inlet 27 into which drilling mud or fluid may be introduced through line 29 controlled by valve 30. Line 29 has connection with the outlet of a mud pump 32 and the inlet side of mud pump 32 is connected to a mud source (not shown), for example, a mud pit or tank adjacent the well head. Lateral outlet 35 of casing head 13 is connected through valve 36 and line 37 with the same or another mud source or reservoir.

As shown in FIGURE 1, inner casing string 12 extends up through the blowout preventers 16, 17 to be sealed around thereby. Before commencing cementing of the well 10, drilling mud or fluid is pumped by pump 32 from the source thereof with valve 30 open so that the mud enters the gas jet or nozzle 22. Gas control valve 38 is open to permit flow of inert gas under high pressure through the nozzle. The gas is delivered from a suitable source of high-pressure inert gas such as that shown in copending United States of America patent application Serial No. 85,288, filed January 27, 1961, and entitled "Gas Method and Apparatus." Said application S.N. 85,288 shows a supply of inert gas such as nitrogen or carbon dioxide which may be transported at low pressure to a well site and which will deliver inert gas at high pressure and at controlled temperature at the well site. The gas supply according to that application is not limited by transportation regulations pertaining to high-pressure limitations of pressure vessels and a supply of inert gas such as nitrogen gas may be delivered at pressures of 10,000 p.s.i.g. or higher, as desired. The gas is delivered through valve 38 to nozzle 22 where the mud is introduced therewith through lateral inlet 27 of the nozzle. The drilling mud or fluid is aerated or gasified to contain a very large proportion of gas in small-size bubble form. Because of the solubility characteristics and inertness of nitrogen, or the like, nitrogen remains mainly in small-bubble form, a proportion of the nitrogen being in solution, whereas air, or the like, having different solubility characteristics than nitrogen, or the like, will tend to break down the mud into its various constituents. Nitrogen does not break down the mud in this manner. The mud aerated with inert gas thereby becomes of appreciably lighter gravity or weight and this condition of the mud is maintained by maintenance of the high pressure thereon.

Gas-mud mixture concentrations may be conveniently expressed in the form of "solution ratios," solution ratio being defined as the ratio of volume of standard gas at standard temperature and pressure, expressed in cubic feet, to volume of mud or other liquid expressed in 42-gallon barrels. The solution ratio for practicable operation may be of a magnitude up to about 4000 s.c.f. of gas to one 42-gallon barrel of mud.

The aerated mud is circulated through body 18 and down through string 12 to be discharged from the open lower end of string 12 into the annular space surrounding the casing in the well hole. The lower end of casing 12 fits more or less loosely within the bore of well 10, the casing being somewhat smaller in diameter than the hole drilled to receive the casing. Aerated mud fills the annulus exterior of the casing wall and within the well bore, displacing unaerated mud theretofore present and causing the unaerated mud to be circulated out of the

well through the annular spaces between casing 12 and the well hole and between casings 11, 12, and line 37. Once substantially all of the unaerated mud has been replaced by aerated mud, the mud circulation may be terminated by closing valves 30, 38 or valve 21. Valve 36 is left open so that cement slurry may be introduced following the aerated mud.

The well is now in condition for cement slurry introduction at relatively low pressure. The mud therein is aerated, as described, to be of light weight.

Referring now to FIGURE 2 of the drawings, cement slurry 40 is introduced into the well bore around the lower end of casing 12 by opening valve 24 connected to the cement source 25 and by closing valve 21 to shut off gas flow while cement is introduced. Cement is pumped through line 23 into line 20 and thence downwardly through casing 12 into the well to the lower end of casing 12 where the cement is discharged around the lower end of the casing, pushing the aerated mud upwardly through the annulus provided and being discharged through lateral outlet 35 of casing head 14 and through open valve 36 and line 37 to the mud supply or reservoir. The amount of cement pumped in is determined by the extent that it is desired for the cement to rise around the outside of casing 12 at cement-mud interface 41. The casing can be cemented all the way or only part way from its lower end up to the lower end of casing 11.

After the desired amount of cement slurry has been pumped into the well through casing 12 to bring the mud-cement interface 41 (of FIGURE 2) to the desired level after the cement in the interior of casing 12 has been discharged from the lower end of casing 12, a displacing fluid, liquid or gas, is introduced above the cement in casing 12 to displace the cement downwardly therefrom. The inert gas from nozzle 22 is convenient for this purpose. In view of the fact that the gas is inert and dry, it does not contribute to corrosion in the well apparatus, but instead minimizes corrosion. The gas is supplied at pressures sufficient for the displacement without additional pressuring thereof being necessary. However, other fluids may be employed for the displacement, if desired.

After sufficient pressured gas (or other fluid) has been introduced to bring gas-cement interface to the desired point 43, FIGURE 3, then valve 36, which has been open during the displacement to permit escape of aerated mud, is closed. The displacing inert gas (or other fluid) is maintained by closing of valve 21, and time for setting of the cement is allowed. The cement setting time is determined by the type of cement used, by the accelerators used, if any, and by the amount of nitrogen introduced into the cement to aerate the cement. The cement slurry, if aerified in the manner described for the mud, has increased internal pore space and thereby requires less setting time. Further, aerification of the cement slurry decreases cement loss into the formation because aerified cement resists channeling flow into the formation. Still further, aerification of the cement slurry minimizes internal separations of the cement slurry so that the cement slurry remains of uniform properties throughout. Also, fluid loss reduction decreases setting-up time of the cement.

In FIGURE 3 of the drawings, there is also indicated a zone 44 around well 10 where the wall of the well hole is inclined to slough off or collapse, or is porous tending to become open to passage of fluid under pressure laterally out of the well. Because the cement is normally introduced under pressure and the pressure exerted by normal weighted mud above the cement is added to the cementing pressure, the pressure is often sufficient to cause mud or cement to be carried into formation 42 and lost. However, with the mud weight decreased due to aeration of the mud, the pressure is decreased to such an extent that cement will not bypass or channel out of the well

to be lost in formation 44 but instead will be retained in place to seal off formation 44 from the well.

After the cement has been held in the well for a sufficient time to set, the gas pressure or the pressure of other displacement fluid may be relieved. Lubricator 18b or any other type of device known in the art through which tools may be inserted into the well may be employed to insert a perforating apparatus 48 into casing 12. Apparatus 48 may, for example, be lowered by a wireline 49 to a point opposite oil or gas formation 50 at the cemented lower end of casing 12 where the same is desired to be perforated. Perforator 48 includes seal 52 therearound which is set to seal the perforating gun to the interior of casing 12. Inert gas is then introduced in the manner described above the perforating gun which is then actuated to perforate the casing as indicated at perforations 53. The pressure of gas above the perforator precludes the perforator from being blown up the hole by the well coming in or by force of explosive gases. Thus, the perforating of the casing is carried out under safe conditions and without chance of blowing out through the casing. Since the inert gas, such as nitrogen, is at a high pressure of up to 10,000 p.s.i.g. or higher, as desired, the gas serves as a positive non-combustible check on the perforating operation. This procedure is useful mainly only in the case of tubingless completions. After perforating has been completed, the gas pressure may be relieved by opening valve 24, the cement supply being disconnected therefrom, and withdrawal of the perforating gun from the casing accomplished through the lubricator 18b. This relief of gas pressure may often be utilized to bring in the production from the well. In this case, production may be controlled, for example, by introduction through lubricator 18b of a back-pressure valve (not shown) to seat at an appropriate point in the casing. The back pressure control apparatus may be set while the gas pressure is still in casing 12, seal 52 being released to permit withdrawal of the perforator before the back pressure apparatus is set.

In the case of completions other than tubingless completions, a different procedure is usually employed. Referring now particularly to FIGURE 5 of the drawings, well 10 is shown after removal of all well-head equipment above casing head 13, and after installation of casing head 50, which surmounts casing head 13 and supports casing 12 in the well, of tubing head 51, which surmounts casing head 50 and supports a tubing string 52 inside casing 12, and of master valve 53, which surmounts tubing head 51 and can be closed to control pressures within tubing 52. An adapter 18' is connected above master valve 53, and has a lateral outlet 55 to which line 20 is connected. Lubricator 18b, or a suitable substitute, is connected above adapter 18' for insertion of tools into the tubing in the well.

Packer device 56 seals the annulus between tubing 52 and casing 12. A circulating sleeve 57, or any other suitable device for valve-controlled flow between the tubing interior and the annulus is provided above the packer. Such flow may be instituted for the purpose of circulating inert gas into, and mud out of, the annulus above the packer, the mud exiting through one of the lateral outlets 58 of tubing head 51, flow through these being suitably controlled by valves, not shown. The mud may be so circulated out, or not, as desired.

Perforator 59 carried at the lower end of wire line 60 is lowered to the level of the formation where it is desired to perforate, valve 53 being open and lubricator 18b controlling the pressure and allowing entrance of the perforator. The perforator is actuated from the surface, and perforations 53b through casing 12 and cement 40, and perforations 53a through the tubing results. Pressured inert gas injected through pipe 20 into the tubing above the perforator holds down the perforator. The well may be brought in by releasing the gas and removing the perforator.

For testing the cement after setting, the inert gas thereabove is released at the well head, so that any leaks may be detected and closed. More cement may be introduced through the casing or tubing, depending on the form of the method employed, after which inert gas may be introduced to squeeze the cement into the leaks to seal them. After setting, the cement may again be tested for leaks in the described manner. The testing for leaks, is, of course, done before perforating.

While a preferred embodiment of the invention has been shown and described, many modifications thereof may be made by persons skilled in the art without departing from the spirit of the invention, and it is intended to protect by Letters Patent all forms of the invention falling within the scope of the following claims.

We claim:

1. Method for cementing in wells wherein the zone of the well to be cemented is filled with a weighted fluid, comprising, at the well site, pumping a stream of liquified inert gas to increase its pressure, heating the pumped liquified gas to vaporize the gas to form high pressure inert gas, gasifying a stream of said weighted fluid drawn from a supply thereof at the surface with said high pressure inert gas prepared at the well site, circulating the gasified fluid into the well to displace said weighted fluid therefrom, circulating a volume of cement slurry into the well to the zone of the well to be cemented, and permitting the cement slurry to set in the well.

2. Method according to claim 1, including directing

30 819,229

said cement slurry to the zone of the well to be cemented by injecting said high pressure inert gas prepared at the well site behind the cement slurry.

3. Method according to claim 1, said liquified inert gas being liquid nitrogen.

4. Method according to claim 1, said liquified inert gas being carbon dioxide.

5. Method according to claim 1, said gasification of said weighted fluid being such that the solution ratio, inert gas/weighted fluid, is in the range from about 50/1 to about 4000/1.

10 6. Method according to claim 1, including also gasifying said cement slurry with said high pressure inert gas prepared at the well site.

15 7. Method according to claim 1, including running a perforating device into the well after said cement slurry is set, passing said inert gas prepared at the well site into the well above said perforating device to provide a non-combustible condition in the well, and operating the perforating device to open the well to production.
